(57) **CLAIM**

The ornamental design for an overhead console for in-car video system, as shown and described in FIGS. 1-6.

DESCRIPTION

FIG. 1 is a bottom perspective view of an overhead console for in-car video system showing our new design;

FIG. 2 is a bottom view thereof;

FIG. 3 is a left side view thereof, the right side of which is a mirror image thereof;

FIG. 4 is a front view thereof;

FIG. 5 is a rear view thereof; and,

FIG. 6 is the bottom perspective view of FIG. 1 showing the display extended.
